UNITED STATES PATENT OFFICE.

ABRAHAM H. BRICKER, OF BROOKLYN, NEW YORK, ASSIGNOR TO JACOB MARCUS, OF BROOKLYN, NEW YORK.

WAISTBAND LINING AND METHOD.

Application filed November 12, 1926. Serial No. 148,083.

My present invention relates to an improvement in waist bands and the method of making and applying the same and more particularly to a waist band to be used in trousers and similar garments and to the method by which the waist band is constructed and attached to the garment. I am aware that heretofore it has been proposed to hemstitch a lining material, to provide the same with a stiffening member, and to connect the hemstitched lining to the cloth forming the trousers or other similar garment and then to fold the cloth adjacent the line of stitching by which the hemstitched lining and the cloth are connected to produce a band in which the hemstitch feature gives the appearance of hand work. In so constructing and applying the waist band lining, however, much difficulty is experienced in making the work even and uniform.

The object of my invention is the same as that heretofore sought in the form of trouser lining to which reference has hereinbefore been made, namely to provide a lining which is so constructed and applied as to give the appearance of hand work. With the improvement, however, by overcoming the difficulties to which I have referred in so constructing the lining that a uniformly even and straight seam may be easily made by a machine in connecting the lining to the goods or cloth of which the trousers are made. To this end in carrying out the invention I employ a stiffener member which by folding or otherwise along one edge portion produces an edge of sufficient thickness to act as a guide for the machine in making the stitch by which the lining is connected to the cloth of the garment, it being understood as will be hereinafter more particularly described that the lining and stiffener member are first connected by a suitable stitch which when the lining is in place in the garment makes the work appear as if it were hand made.

In the drawing Figure 1 is a plan illustrating the manner in which the waist band lining and cloth of the garment are made and connected in accordance with my invention.

Fig. 2 is an edge view taken on line 2—2, Fig. 1.

Fig. 3 is an inside view of the lining and a part of the cloth of the garment after these have been connected and turned to their position in use, and

Fig. 4 is an edge view on a materially enlarged scale on line 4—4, Fig. 3.

By referring to the drawing it will be seen that in carrying out my invention the waist band lining made in accordance therewith comprises a stiffener member 10 made of canvas or like material as is customary in this art. This canvas stiffener member is cut or made in strips and one edge portion thereof is folded on itself as indicated at 11. In completing the waist band lining itself I also employ the customary lining material 12. This is also cut in a strip appreciably wider than the strip of stiffening material. A part of one edge portion of the lining member 12 is placed on the opposite edge portion of the stiffener member 10 and these parts secured to each other by a line of stitching 13 which runs substantially parallel to the opposite edge 14 of the stiffener member. The lining member 12 is then folded over the edge 14 and made to extend across and beyond the opposite face of the stiffener member 10. With the stiffener member and the lining secured to each other by the line of stitching 13 the adjacent parts of the stiffener and lining are made to conform to each other and are then connected at the folded edge portion 11 of the stiffener member by a line of stitching 15 which is preferably a zigzag stitch or some other more or less artistic stitch which will give the finished article a neat and satisfactory appearance. It is to be noted that the edge 16 of the stiffener member adjacent this line of stitching 15 is sufficiently thick to form a guide in securing the waist band lining to the trousers material.

With the waist band lining constructed as hereinbefore described the edge portion 17 extends appreciably beyond the stitch 15. As thus constructed the waist band lining is placed upon the trousers material 18, or the material of any garment to which the waist band lining is to be applied, with the outer face of the waist band lining adjacent the outer or obverse face of the garment material as clearly indicated in Figs. 1 and 2 of the drawing. With the parts in this position they are connected by a line of stitching 19 made by a suitable sewing machine in which operation the edge 16 forms a guide for the machine in order to insure the line of stitching being straight and uniform. With the parts thus constructed the garment material 18 is fold-

- ed over on the line 20 so as to bring the obverse or outer surface of the material outermost and the outer surface of the lining member of the waist band lining innermost, where-
5 by in so doing the edge of the lining material 12 adjacent the stitch line 15 will be folded over the edge 16 of the edge portion 11 of the stiffener member and the parts will assume the position shown in Figs. 3 and 4
10 in which the more or less fancy stitch 15 will be readily visible and will not only give the work the appearance of being hand made, but also will be even and uniform throughout the entire length of the waist band lining.
15 I claim as my invention:
1. The method of constructing a waist band lining and securing the same to a garment material consisting in folding one edge portion of a strip of stiffener material on itself leav-
20 ing the opposite edge thereof unfolded, placing a strip of lining material on the strip of stiffener material and securing one edge portion of the strip of lining material to the strip of stiffener material adjacent the unfolded
25 edge thereof, then folding the strip of lining material over the unfolded edge of the strip of stiffener material, connecting the folded edge portion of the strip of stiffener material to the adjacent portion of the strip of lining
30 material by a zigzag stitch with a portion of the lining material extending beyond the edge of the folded edge portion of the stiffener material, placing the thus formed lining on a garment material and securing the same to
35 the garment material by a line of stitching running along the edge of the folded edge

portion of the stiffener material and passing only through the garment material and that portion of the lining extending beyond the folded edge portion of the stiffener material, 40 and then turning the garment material and the lining material over on the line of stitching connecting the garment material to that portion of the lining material which extends beyond the edge of the folded edge portion of 45 the stiffener material.

2. In trousers and like garments, a waist band lining comprising a stiffener member and a liner member, one edge portion of the stiffener member being folded on itself to 50 provide an edge of appreciable thickness and the opposite edge thereof being unfolded, one edge portion of the liner member being connected to the unfolded edge portion of the stiffener member by a line of stitching with 55 the liner member folded over the said unfolded edge portion of the stiffener member with the other edge portion of the liner member extending beyond the edge of the folded over edge portion of the stiffener member, the said folded edge portion of the stiffener member being connected to the adjacent portion of the liner member by a zigzag line of stitching, the thus formed waist band lining being connected to the trousers material by a 60 line of stitching running only through the same and the liner member adjacent the edge of the folded over edge portion of the stiffener member. 65

Signed by me this 30th day of October, 70
1926.

ABRAHAM H. BRICKER.
